FINGER BAR FOR USE WITH STRINGED
MUSICAL INSTRUMENTS

Henry J. Spina, Albany, N. Y.

Application October 22, 1932, Serial No. 639,102

3 Claims. (Cl. 84—319)

My invention more particularly relates to a bar or steel of the character used by musicians in playing a Hawaiian guitar or other stringed musical instrument.

One of the objects of my invention is the provision of a bar of the foregoing character provided with means by which a musical note on one of the strings may readily be lowered a half tone and a minor chord produced. Heretofore in using a steel bar, in order to produce a minor chord, it has been necessary for the player to hold the steel bar diagonally across the strings in order to engage the string on which the desired lowered tone is to be produced at the correct point. It is difficult, however, for the player to manipulate the bar in this manner. Furthermore, he can use only the second and third strings at the time that the minor chord is produced.

It is to be understood that in use the strings are not depressed by the bar sufficiently to bring them into engagement with a fret over which it is located and that the same is unattached to the instrument when in playing position. The usual steel bar has a substantially continuous and preferably straight lower edge.

My invention provides means by which a minor chord may be produced while holding the bar transversely across the strings in the normal manner and at the same time all six strings of the instrument may be used for producing the chord.

Another advantage of my invention resides in the fact that the player may readily produce a diminished fifth on three of the strings, a dominant seventh and the device may also be utilized in melody work.

My invention will best be understood by reference to the accompanying drawing in which I have illustrated a preferred embodiment thereof and in which

Fig. 1 is a fragmentary perspective view of a portion of a Hawaiian guitar with the bar embodying my invention held by the player above the strings thereof;

Fig. 2 is a perspective view of a bar embodying my invention; and

Fig. 3 is a fragmentary side elevation illustrating the use of the bar in connection with the strings of the instrument.

Like reference characters indicate like parts throughout the drawing.

Referring to the drawing, 10 is a Hawaiian guitar provided with the usual neck 11 on which are mounted the usual frets 12. The strings are indicated generally at 13. A steel bar 14 is preferably provided with a curved finger clip 15 which

is engaged by the index finger of the left hand of the player, as illustrated in Fig. 1, the clip affording a convenient means for supporting the bar or steel on the finger of the player. The bar 14 is preferably of sufficient length to exceed the span 5 of said strings when held transversely of and above the same.

In accordance with my invention, a member 16, preferably though not necessarily formed of metal and angular in form extends laterally from the bar 14. All parts of the member 16 are normally located above the lower edge of the bar 14 and above the level of the strings when the bar is held against the same in normal playing position, the parts being so arranged that when the member 16 is depressed the end of the part 161 depresses a string located beneath the same, it being understood that in practice the string is not depressed an amount sufficient to bring the same into engagement with a fret. The width of the part 161 is less than the distance between two adjacent strings. When a string is depressed, its tension is increased and the pitch of the note produced thereby is correspondingly raised. At the same time, as the member 161 is depressed, the end 25 thereof describes the arc of a circle about the lower edge of bar 14 as a center, the end of the member 161 sliding along the string underneath towards the left as viewed in Fig. 3 thereby shortening the vibrating portion of the string and raising the pitch thereof. By varying the amount that the string is depressed therefore, the player may vary the pitch and produce the exact tone desired.

It will be noted that the finger piece 15 and the 35 laterally extending bar 16 are so located on the main bar 14 that when the bar is held by a finger of the left hand in the playing position indicated in Fig. 1, the bar 16 faces the keys of the instrument.

As an example of the use of the device, let it be assumed that the chord in the key of A major is to be produced. When the bar is held above the fret 121 and the strings depressed, and the pick, which it will be understood is usually carried on the thumb of the right hand, sweeps over the strings 133, 132 and 131, the chord formed by the notes A, C sharp and E, respectively, is produced when the bar is held above fret number 40 12. The string 134 is an octave below the string 131, the string 135 an octave below the string 133 and the string 136 an octave below string 134. When the pick sweeps over the strings a major chord, therefore, is produced.

The member 16 is so mounted on the bar 14 that when the bar is held against the strings in the usual manner, the lateral extension 161 of the member 16 is located above the level of the 5 strings of the instrument and specifically above the second string 132, and is in such a position that either the second or third finger, as desired, may be positioned above the lateral extension 161 of the bar and used to depress the same. In 10 Fig. 1, I have for convenience, shown the third and fourth fingers bent back away from the neck in order more clearly to show the position of the second finger over the lateral extension 161. It will be understood that in practice the third and 15 fourth fingers, or the fourth finger alone, in case the third finger is used for depressing the lateral extension 161, is laid upon the strings behind the bar 14 in order to stop vibration thereof. Assuming that the bar 14 is located above the 20 fret 121 and engaging the strings but with pressure insufficient to bring them into engagement with the fret 121 above which the bar is at this time located, then by depressing the lateral extension 161 and the string 132 which it engages 25 in the manner illustrated in Fig. 3, the vibrating portion of this string is lengthened by the distance between the fret 121 and the portion of the laterally extending member engaging the string with the result that the note produced by the 30 string 132 is C natural rather than C sharp and the strings 133, 132 and 131 produce the minor chord of A, C and E, the other three strings producing the tones E, A and E, as above, so that the 35 tones produced by all six of the strings make up the minor chord. The subdominant minor chord may similarly be produced, it being understood that the major and minor chords are the same for the dominant. Similarly, the major chord can be changed into a minor chord by depressing 40 the laterally extending piece at any fret. The device may also be used for producing the dominant of the major chord. For example, when the bar or steel 14 is held over fret 15 (counting from the right in Fig. 1) which is the C chord, by 45 dropping the laterally extending member 161 against and depressing the third string 133, B flat note is produced which is the seventh of the dominant major chord.

By the use of the lateral extension when held 50 over the first string 131, a diminished fifth may be produced by depressing the first string by the lateral extension and playing only the first three strings 131, 132 and 133. The device is also useful in melody playing on the lower five strings in 55 which case a minor tone may be produced by depressing the lateral extension on the string 132.

While I have described my invention in its preferred embodiments it is to be understood that the words which I have used are words of description rather than of limitation and that 60

changes within the purview of the appended claims may be made without departing from the true scope and spirit of my invention in its broader aspects.

What I claim is:

1. A device for playing a stringed musical instrument comprising a tone bar having a smooth continuous lower edge adapted to extend freely across and above and engage the strings of said instrument and provided with an element secured 10 to said bar at an intermediate portion thereof and extending laterally therefrom and of a width sufficient transversely of said strings to engage a single string at the string engaging portion, said element being located in a position to be engaged 15 by a finger of the player, the free end of said element being located above and near the level of the lower edge of said bar when the latter occupies a playing position, whereby the end of said element may be brought into engagement with a 20 string by a finger of a player when said bar is held in playing position transversely of and over said strings of said instrument.

2. A device for playing a stringed musical instrument comprising a tone bar having a smooth 25 continuous lower edge adapted to extend across and above and engage the strings of said instrument and provided with an element extending laterally therefrom and facing the keys of the instrument when held in playing position, 30 said element having a width sufficient transversely of said strings suitable to engage a single string only, at the string engaging portion, said element being located in a position to be engaged by a finger of the player, the free end of said element being located above and near the level of said bar when the latter occupies a playing position whereby the end of said element may be brought into engagement with a string by a finger of a player when said bar is held in playing 35 position transversely of and over said strings.

3. A device for playing a Hawaiian guitar comprising a tone bar of sufficient length to span said strings when held transversely thereof and having a lower edge adapted to extend across 45 and above and engage the strings of said instrument, said bar being provided with a finger piece adapted to be engaged by a finger and held thereby in playing position and with an element extending laterally from the side of said bar fac- 50 ing the keys of said guitar when held in playing position and of sufficient width to engage a single string only at the string engaging portion, said element being located in a position to be engaged by a finger of the player whereby the end 55 of said element may be brought into engagement with a string of said instrument when said bar is held in playing position transversely of and over said strings.

HENRY J. SPINA. 60
